(57) **CLAIM**

The ornamental design for a jig head for fishing lure, as shown and described.

DESCRIPTION

FIG. 1 is a top perspective view of a jig head for fishing lure; FIG. 2 is a left side view of a jig head for fishing lure, with the right side view being a mirror image thereof; FIG. 3 is a front view of a jig head for fishing lure; FIG. 4 is a rear view of a jig head for fishing lure; FIG. 5 is a top view of a jig head for fishing lure; and, FIG. 6 is a bottom view of a jig head for fishing lure. The broken lines (dot-dot) in the drawings illustrate portions of the jig head for fishing lure or the environment incorporating the jig head for fishing lure that form no part of the claimed design. The broken lines (dash-dot-dash) immediately adjacent to the shaded area in FIGS. 1-4 represents unclaimed boundaries of the design. The solid lines forming concentric circles that are surrounded by broken lines (dot-dot) in FIG. 5 illustrate portions of the jig head for fishing lure which lies beneath the broken lines.
